UNITED STATES PATENT OFFICE

2,471,740

METAL FURNITURE

Bertis F. Hamilton, Columbus, Ind., assignor to
 Hamilton Manufacturing Corporation, Columbus, Ind., a corporation of Indiana

Application December 1, 1944, Serial No. 566,043

4 Claims. (Cl. 155—194)

1

My invention relates to metal furniture, and more particularly to that type of metal furniture in which tubular legs support a table-top, the seat of a stool or chair, or the like. It is the object of my invention to produce an article of metal furniture in which the tubular legs can readily be removed from or applied to the element they are to support in order to permit the article to be shipped in knocked-down condition and readily erected. More specifically, it is my object to produce a clamp which can be permanently attached to the table-top or chair-seat and which will removably receive and firmly hold the upper end of a tubular leg. A further object of my invention is to produce a clamp which can be simply and economically manufactured.

In carrying out my invention, I form the clamp of a single sheet-metal stamping secured to the inner face of a depending peripheral flange on the element to be supported. Desirably, the upper end of the leg to be received in the clamp is made non-circular in cross-section, and the clamp is formed to embrace the non-circular upper end of the leg. The edge portions of the metal forming the clamp extend outward radially from the leg in spaced relation to each other and receive one or more clamp-bolts by means of which the clamp may be tightened. The clamp includes an ear or flange bent into a horizontal plane to overlie and transmit loads to the upper end of the leg which the clamp receives.

The accompanying drawing illustrates my invention: Fig. 1 is a side elevation of a stool; Fig. 2 is a fragmental vertical section on the line 2—2 of Fig. 3 showing, on an enlarged scale, the clamp and its associated leg; Fig. 3 is a horizontal section on the line 3—3 of Fig. 2; Fig. 4 is a top plan view of the clamp; Fig. 5 is a fragmental side elevation of the upper portion of the stool with the upholstery removed therefrom; and Fig. 6 is an elevation of the inner face of the clamp.

In the drawing, I have illustrated my invention as embodied in a stool, but it is to be understood that it is capable of use in other articles of furniture. The stool shown comprises a seat 10 covered with upholstery material 11 and supported by a plurality of legs 12. The seat 10 is desirably a sheet-metal stamping formed with a downwardly projecting cylindrical flange 13 at its periphery. At places where legs are to be attached to the seat, vertically spaced portions of the seat-flange 13 are offset inwardly as indicated at 14, such offset portions being substan-

tially coplanar. The lower ends of the legs are held in proper relation by a ring 15 to which each of them is attached.

The clamp by which each leg is secured to the seat is also formed as a sheet-metal stamping. Each clamp comprises a substantially plane outer wall 16 and side walls 17 embracing the upper end of the associated leg 12. In order that the leg 12 may be prevented from turning in the clamp, its upper end is partly flattened to provide, over the vertical extent of the clamp, a plane outer wall 18 disposed in juxtaposition to the plane outer wall 16 of the clamp. Opposite the outer clamp-wall 16, the edge portions 20 of the side walls 17 are bent to extend inwardly of the seat in parallel, spaced relationship, and one of such edge portions is provided with a bent lip 21 adapted to engage the outer edge portion. The two edge portions 20 are provided, between the lip 21 and the interior of the clamp, with one or more pairs of aligned holes for the reception of clamp bolts 23.

The outer wall 16 of each clamp is provided with two horizontally extending, outwardly offset portions 25 spaced correspondingly to and engaging the offset portions 14 on the seat-flange 13. The clamp is secured in place on the seat-flange by rivets 26 which extend through the engaging offset portions 14 and 25.

At its upper end, the outer clamp-wall 16 is provided with an ear 28 bent inwardly of the clamp into a horizontal position to overlie the upper edge of the flattened portion of the leg 12.

In the manufacture of the stool shown in the drawing, the seat, with the leg-clamps attached by the rivets 26, is upholstered, the upholstery material 11 extending downwardly over the outer surface of the flange 13 and concealing the rivets 26. Ordinarily, the stool will be shipped in knocked-down condition, with the legs removed from the seat. To apply the legs to the seat it is necessary only to insert the upper end of a leg 12 in each of the clamps and tighten the bolts 23. The flat face 18 at the upper end of each leg insures that the leg will be properly oriented about its axis in the associated clamp. The outwardly offset portions 25 in the front clamp-wall provide a space for the reception of the heads on the inner ends of the rivets 26 and prevent such heads from interfering with insertion of the leg into the clamp. The ears 28 definitely locate the respective legs 12 in the proper vertical position in the clamps and transmit to the legs any load imposed on the clamp.

I claim as my invention:

1. In an article of furniture having a seat and supporting legs therefor, said seat including a downwardly extending flange of sheet metal, clamps secured at intervals against the inner face of said flange, each of said clamps having a leg associated with it, each of said legs being formed of metal tubing flattened on one side for a distance from its upper end, each of said clamps being formed of a piece of sheet metal bent to surround the upper end of the associated leg and having a plane wall-portion in juxtaposition to the flattened side of said leg, the plane wall-portion of each clamp lying against the inner face of said flange and having its upper edge bent inwardly to overlie the upper end of the associated leg, the ends of said piece of sheet metal opposite said plane wall portion being bent to form ears extending in parallel relation and inwardly of the seat, and one or more clamp-bolts passing through said ears.

2. In an article of furniture having a seat and supporting legs therefor, said seat including a downwardly extending flange of sheet metal, clamps secured at intervals against the inner face of said flange, each of said clamps having a leg associated with it, each of said legs being formed of metal tubing flattened on one side for a distance from its upper end, each of said clamps being formed of a piece of sheet metal bent to surround the upper end of the associated leg and having a plane wall-portion in juxtaposition to the flattened side of said leg, the plane wall-portion of each clamp lying against the inner face of said flange, the ends of said piece of sheet metal opposite said plane wall-

portion being bent to form ears extending in parallel relation and inwardly of the seat, and one or more clamp-bolts passing through said ears.

5. The invention set forth in claim 2 with the addition that the plane wall-portion of each clamp and the adjacent portion of said flange are provided with contacting portions offset toward each other.

10. 4. In an article of furniture having a seat and supporting legs therefor, said seat including a downwardly extending flange of sheet metal, said flange being provided at intervals with inwardly offset portions to form recesses in the outer face of said flange, sheet-metal clamps disposed within said flange and provided with outwardly offset portions respectively contacting the inwardly offset portions of said flange, and means 15 passing through each pair of contacting offset portions and having portions located in the associated recess for securing each clamp to said flange, each of said legs having its upper end secured in one of said clamps.
